UNITED STATES PATENT OFFICE

MARTIN EULE, OF BERLIN-SPANDAU, AND ERICH ANDERS, OF BERLIN-CHARLOTTENBURG, GERMANY, ASSIGNEES TO SIEMENS-SCHUCKERTWERKE AKTIENGESELLSCHAFT, OF BERLIN-SIEMENSSTADT, GERMANY, A CORPORATION OF GERMANY

MULTIPLE HEAT EXCHANGE COIL

Application filed July 16, 1931, Serial No. 551,148, and in Germany November 30, 1929.

Our invention relates to multiple heat exchange coils as used in feed-water heaters and superheaters of steam plants.

To facilitate the assemblage of the heating surfaces in heat exchangers, for example feed-water heaters or superheaters, consisting of tubing or piping, the heating surfaces are mostly subdivided into separate packets or groups of tubing. The present invention relates to such a packet of tubing which differs, however, from the arrangements known in the art by the fact that it consists of two or more tube lengths joined in parallel and which are helically wound in contrary directions into the shape of flat cylinders the lateral surfaces of which are parallel to one another, the coils of tubes thus formed being inserted into one another.

A packet of tubing of that kind has certain advantages compared with the packets of tubing hitherto known. If only one tube length is employed and the flow area of the packet of tubing has to be increased, a tube having a larger internal diameter must be used. Consequently, when larger flow areas are required, a size of pipe must be used which is difficult to bend. As, besides, the radius of curvature which must be observed at each bending of the tube increases with the size of the tube, the overall dimensions of a packet, made of a single tube length, also increase with the flow area of the tube. According to our invention a larger flow area can easily be obtained by simply increasing adequately the number of tube lengths joined in parallel to form a packet. By this means the given overall dimensions of the packet of tubing need not be exceeded and the bending of the tubes does not present any particular difficulty.

With regard to the possibility according to our invention, of uniting into a packet the tube coils wound in contrary directions by inserting them into one another, two cases come into consideration. As long as it is not intended to insert the spirals, formed by the tubes and coiled in contrary directions, so far into one another that their return or end bends lie exactly in coaxial relation, no obstacle is encountered in bringing the spirals

into position. Otherwise it must be taken into account that owing to the tubes being coiled in contrary directions the longitudinal sides of the different tube spirals would intersect. If, in order to obtain a better utilization of the available space, the coils wound clockwise and counter-clockwise are to be inserted so far into one another that their return bends are disposed exactly coaxially, then, according to our invention, the distance between the two parallel sides of the flattened coils is made smaller than the diameter of the return bend. The bending of the individual tube coils to be inserted into one another remains in this case an easy matter. The tubes are first wound into flat spirals, and then all coil lengths on one side are pressed in further toward the imaginary center line drawn between the return bend centers of the coils, until the distance between the parallel sides of the coil is reduced by at least the diameter of the tubing used in the coils for the reason apparent from the detailed description of the drawings.

A packet of tubing made in the aforescribed manner by inserting, for example, two coils wound in contrary directions into each other, is illustrated in the accompanying drawings.

Fig. 1 shows as a whole the arrangement of a superheater section 1 and of a feed-water heater section 2, both consisting of packets of tubing constructed in the one or the other manner according to the invention.

Fig. 2 shows a section on the line 2—2 in Fig. 1.

Fig. 3 shows how the tube spirals wound clockwise and counter-clockwise may be shaped in order to render it possible for them to be inserted into each other far enough to place all return bends exactly into axial alinement, as illustrated in Fig. 2.

Fig. 4 is a cross-sectional view, on an enlarged scale, taken on the line 4—4 of Fig. 2 and represents a suitable manner of supporting and suspending the tubes bent as in Fig. 3.

Fig. 5 shows the other shape mentioned above for the packet of tubing in which the

tube spirals are not placed into one another so far as to axially align the return bends.

Fig. 6 shows an arrangement for the suspension of tubes disposed as in Fig. 5 and 5 represents a section through 6-6 in Fig. 5, on an enlarged scale, and

Fig. 7 shows details of the tube suspension illustrated in Fig. 6 and is a sectional view taken on line 7-7.

10 From the diagrammatic representation in Fig. 3, the necessity will be plainly seen for making in each case the distance between the two parallel sides of the flattened coil smaller than the diameter of the return bends, if the 15 two contrary wound spirals are to be placed so far into one another that their return bends come exactly into axial alignment, i. e. that they can be mounted on a common arbor as shown in Fig. 3. In Figs. 1, 2 and 3, 3 20 is a counter-clockwise-wound tube coil and 4 a clockwise-wound tube coil.

To secure the individual windings in their positions relative to one another, distance rings 5 are placed between the windings and 25 a tubular member 6 is passed through each return bend. The tubular member 6 is supported by a plate or disk 7 resting on a nut 8 threaded onto a central suspension rod 9. At its top end the tubular member 6 is centered by rings 10 and 11. If the coils are 30 to be so wound that the tubes joined in parallel are always at the same distance from each other then the spirals can be placed into one another only as far as shown in Fig. 5. 35 In that case the tubes can no more be suspended in the manner shown in Fig. 4, but specially formed carrying brackets 12 and 13 become necessary. These brackets are shown in Figs. 6 and 7. In Fig. 6 the path of each 40 coil is indicated in dash-dot lines. The carrying brackets here also rest upon a plate or disk 14 held by the suspension rod 16.

We claim as our invention:

1. A packet of tubing for heat exchangers 45 or the like, consisting of a plurality of tube lengths, wound into similarly shaped independent helical coils, some running clockwise and others counterclockwise all of said coils being coaxially disposed relatively to one another, each of said coils having the shape of a flattened cylinder, whose lateral surfaces constitute two parallel planes spaced apart from one another, the turns of each coil being inserted between the turns of an oppositely wound coil, the number of spaced parallel planes 50 in which the straight tube portions of the coils are located being equal to the total number of parallel coil sides contained in the packet.

60 2. A packet of tubing for heat exchangers or the like, consisting of a plurality of tube lengths, wound into similarly shaped independent helical coils, some running clockwise and others counterclockwise all of said coils 65 being coaxially disposed relatively to one an-

other, each of said coils having the shape of a flattened cylinder, whose lateral surfaces constitute two parallel planes spaced apart from one another, a distance less than the return bend diameter by at least the tube diameter, the turns of each coil being inserted between the turns of an oppositely wound coil, sufficiently far, to align all adjacent return bends into a common axis, the number of spaced parallel planes in which the straight tube portions of the coils are located being equal to the total number of parallel coil sides contained in the packet.

3. A packet of tubing for heat exchangers or the like, consisting of a plurality of tube lengths, wound into similarly shaped independent continuous coils, some running clockwise and others counterclockwise, each of said coils having the shape of a flattened cylinder, whose lateral surfaces constitute two parallel planes spaced apart from one another, the turns of each coil being inserted between the turns of an oppositely wound coil, the number of spaced parallel planes in which the straight tube portions of the coils are located being equal to the total number of parallel coil sides contained in the packet, and a spacing rack for said tube coils, consisting of two component elements, each arranged to space and support the tubes of adjacent sides of different coils, and a common suspension bar arranged between said elements and having a carrier plate at its lower end, forming a common longitudinal support for said elements.

In testimony whereof we affix our signatures.
